CALF WEANING HALTER

Filed April 25, 1952

UNITED STATES PATENT OFFICE

2,672,846

CALF WEANING HALTER

Ernest Dewey Maynard, Lancer, Ky.

Application April 25, 1952, Serial No. 284,315

4 Claims. (Cl. 119—130)

1.

This invention relates to devices for weaning calves, and in particular to a halter having a metal strap with a disc having prongs extended therefrom on the lower end and a plurality of straps positioned to extend around the head of a calf for retaining the metal strap and disc in position with the strap and disc substantially on the center of the nose of the calf.

The purpose of this invention is to provide a weaning halter that is not uncomfortable and that does not prevent grazing.

Various types of halters have been provided with weaning devices, however, owing to the abuse to which a device of this type is subjected it is difficult to retain a weaning element in position without comparatively heavy harness or other devices that are objectionable or that annoy the calf. With this thought in mind this invention contemplates a halter formed with comparatively few straps and having a metal strap with a disc having prongs extended therefrom mounted on the straps and positioned to be located substantially on the center of the nose of a calf upon which the halter is positioned.

The object of this invention is, therefore, to provide means for mounting a weaning element on a halter whereby the weaning element is retained in position on the center of the nose and wherein the halter is formed of comparatively light weight straps.

Another object of the invention is to provide a weaning halter that is adjustable to stock of different sizes.

A further object of the invention is to provide an improved weaning halter which is of a simple and economical construction.

With these and other objects and advantages in view the invention embodies a weaning halter having a mounting strap extended from a ring positioned below the throat of an animal over the head and behind the ears; another strap extended around the under side of the neck; a strap extended over the forehead above the eyes; a strap extended around the mouth and over the nose, a centrally disposed strap extended from the strap extended over the nose, over the head and connected to the strap positioned behind the ears, and a metal strap having a disc with prongs extended therefrom secured to the strap extended from the strap over the nose over the head to the strap behind the ears.

Other features and advantages of the invention will appear from the following description taken in connection with the drawing, wherein:

Figure 1 is an elevational view illustrating the 55 halter is readily positioned on the head of a

2.

position of the weaning halter on the head of a calf.

Figure 2 is a plan view of the halter with the ends of the straps extended outwardly illustrating the relative positions thereof.

Referring now to the drawing wherein like reference characters denote corresponding parts the improved weaning halter of this invention includes a strap 10 having a disc 11 with outwardly extended prongs, 12 secured thereon with bolts 13, and a halter having a centrally disposed nose strap 14 to which the strap 10 is secured with rivets 15, a nose strap 16, a neck strap formed with sections 17 and 18, a strap 19 adapted to extend over the forehead and above the eyes of an animal, and a mounting strap 20 having a ring 21 thereon.

As illustrated in the drawing the metal strap 19 extends from a point 22 on the strap 14 and the lower end is provided with a U-bend which extends over a plate 23, and an end 24 extended from the U-bend is positioned over the end of the strap 14.

The strap 16 extends through an opening 25 between the upper section of the strap 10 and the end 24 and, as illustrated in the drawing the strap 16 is provided with a buckle 26, spaced bands 27, and spaced openings 28 that are positioned to receive the tongue or prong 29 of the buckle. This strap is positioned to extend through the ring 21, as shown in Fig. 1.

The mounting strap 20 is also provided with a buckle as indicated by the numeral 30, bands 31, and spaced openings 32. The extended end of the strap 14 is provided with bands 33 and a buckle 34 and the end 35 of the strap extends through the buckle and back, as illustrated in Fig. 1 to form a loop 36 through which the strap 20 extends.

Section 17 of the neck strap is provided with bands 37, a buckle 38 and a loop 39 through which the mounting strap 20 extends, and the section 18 of the neck band is provided with a similar loop 40 through which the mounting strap 20 extends. The section 18 is also provided with spaced openings 41 that are positioned to receive the tongue or prong of the buckle 38 and this section of the strap is retained in position by bands 42 and 43 on the mounting strap.

The mounting strap 19 is also provided with loops, as indicated by the numerals 44 and 45 and the mounting strap 20 extends through these loops, as shown.

With the parts arranged in this manner the

calf, or the like with the mounting strap 20 extended behind the ears, the strap 16 extended over the nose, the strap 19 over the upper part of the forehead, and through the strap 14, and the sections 17 and 18 buckled below the neck.

By this means the halter is secured in position on the head of a calf and the prongs 12 of the disc 11 extend outwardly from the halter with the prongs on one side of the disc extended perpendicular to the strap 10 and the prongs on the lower side extended outwardly at an acute angle in relation to the straps.

With the parts arranged in this manner the halter may readily be positioned on the head of a calf, or the like and with the prongs positioned as illustrated in Fig. 1 they engage the udder when an attempt is made to nurse and the mother cow will not permit the calf to nurse. With the prongs extended as shown they do not engage the ground in grazing and for this reason the calf may graze freely and may also eat hay and other feed.

In the design shown the weaning element is riveted by the strap 10 to the head strap 14 and the head strap is held in position in relation to the mounting strap 20 by the upper strap 19 and the nose strap 16. The mounting strap is held in position by the neck strap formed with the sections 17 and 18. With the parts supported in this manner comparatively heavy straps are not required and the weaning element is secured in position with comparatively small straps.

It will be understood that modifications may be made in the design and arrangement of the parts without departing from the spirit of the invention.

What is claimed is:

1. A weaning halter comprising a mounting strap positioned to extend from a point below the mouth of an animal around the back of the head and behind the ears of the animal, a ring carried by said mounting strap, a nose strap having both ends extended through the ring and adapted to extend over a nose of an animal around the head of which the mounting strap extends, a neck strap having its opposite ends connected in opposed relation to each other to the mounting strap and extended from the mounting strap and having a buckle therein, a head strap extended from the nose strap to the mounting strap and connected thereto at a point positioned at the back of the head and between the ears of the animal, and a strap with prongs extended therefrom mounted on said head strap and positioned with the prongs extended from the nose of the animal upon which the straps are positioned.

2. A weaning halter comprising a mounting strap positioned to extend from a point below the mouth of an animal around the back of the head and behind the ears of the animal, a ring carried by said mounting strap, a nose strap having both ends extended through the ring and adapted to extend over a nose of an animal around the head of which the mounting strap extends, a neck

strap having its opposite ends connected in opposed relation to each other to the mounting strap and extended from the mounting strap and having a buckle therein, a head strap extended from the nose strap to the mounting strap and connected thereto at a point positioned at the back of the head and between the ears of the animal, and a strap with prongs extended therefrom mounted on said head strap and positioned with the prongs extended from the nose of the animal upon which the straps are positioned, said strap having buckles therein providing adjustment in the lengths thereof.

3. A weaning halter comprising a mounting strap positioned to extend from a point below the mouth of an animal around the back of the head and behind the ears of the animal, a ring carried by said mounting strap, a nose strap having both ends extended through the ring and adapted to extend over a nose of an animal around the head of which the mounting straps extends, a neck strap having its opposite ends connected in opposed relation to each other to the mounting strap and extended from the mounting strap and having a buckle therein, a head strap extended from the nose strap to the mounting strap and connected thereto at a point positioned at the back of the head and between the ears of the animal, a strap with prongs extended therefrom mounted on said head strap and positioned with the prongs extended from the nose of the animal upon which the straps are positioned, said strap having buckles therein providing adjustment in the lengths thereof.

4. In a weaning halter, the combination which comprises a mounting strap positioned to extend from a point below the mouth of an animal around the back of the head and behind the ears of the animal, a ring carried by said mounting strap, a nose strap having both ends extended through the ring and having a buckle therein, a neck strap having its opposite ends connected to the mounting strap in opposed relation to each other and also having a buckle therein extended from opposite sides of the mounting strap, a head strap extended from the nose strap to a point on the mounting strap positioned at the back of the head of the animal, an upper strap extended through the head strap and having loops on the ends through which the mounting strap extends, a metal strap secured to the head strap with rivets, and a disc having outwardly extended prongs thereon secured by bolts to the said metal strap.

ERNEST DEWEY MAYNARD.
